United States Patent Office

Des. 195,600
Patented July 2, 1963

195,600

BOTTLE

Ray O. Neyman, Kansas City, Mo., assignor to Consolidated Thermoplastics Company, Stamford, Conn., a corporation of Delaware

Filed Nov. 2, 1962, Ser. No. 72,356

Term of patent 14 years

(Cl. D58—6)

FIG. 1

FIG. 2

FIG. 3

The bottle side not shown in FIGURE 1 is identical to the side shown in FIGURE 1.

The dominant features of my design reside in the portions shown in full lines.

I claim:

The ornamental design for a bottle as shown and described.
